(57) **CLAIM**

The ornamental design for an electric bicycle, as shown and described.

DESCRIPTION

FIG. 1 is a front and right side perspective view of an electric bicycle embodying my new design;

FIG. 2 is a front and left side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged detail view thereof showing the portion identified in the reference bubble FIG. 9 in FIG. 8.

The broken lines in the drawings illustrate portions of the electric bicycle that form no part of the claimed design.

1 Claim, 9 Drawing Sheets
